UNITED STATES PATENT OFFICE.

JOHN R. GATHRIGHT, OF JEFFERSONVILLE, INDIANA.

COMBINED GRAIN AND OIL CAR.

SPECIFICATION forming part of Letters Patent No. 313,932, dated March 17, 1885.

Application filed December 31, 1884. (No model.)

To all whom it may concern:

Be it known that I, JOHN R. GATHRIGHT, a citizen of the United States, residing at Jeffersonville, in the county of Clarke and State 5 of Indiana, have invented certain new and useful Improvements in a Combined Grain and Oil Car; and I do hereby declare the following to be a full, clear, and exact description of the invention, such as will enable others 10 skilled in the art to which it appertains to make and use the same.

This invention relates to railway-cars for transporting freight.

It is a well-known fact that cars which go 15 east loaded with grain from the great grain regions are frequently returned empty at great expense, and that cars suited for carrying oil have to be returned empty to the oil regions from all directions, because oil-cars are unsuited for carrying anything else.

The object of this invention is to adapt a car to be loaded to its full limit of weight with oil, to carry the same to its destination, and then to be loaded with grain or other 25 freight to its full capacity of weight on its return-trip.

To this end my invention consists in the construction and combination of parts forming a freight-car, hereinafter described and 30 claimed, reference being had to accompanying drawing, which is a side elevation of a car, part in section, illustrating my invention.

A represents car-trucks of any usual construction, upon which the body B is mounted. 35 This body consists of an iron tank of any form suitable for a car-body and suitable to carry oil.

C represents a wooden box or car-body built on top of the iron tank or car B.

40 The box-car C is provided with a wooden bottom, D, raised enough above the top of the tank B to permit free circulation of air between and to preserve the interior of the box-car entirely free from any oil which may leak or slop out of the tank. I have shown the oil-tank as partially separated into two compartments by the slanting form of the upper side thereof, yet united in the middle. This union 45 may take place within the contour of the tank, as shown, or the tank may be separated into two distinct compartments and connected by a pipe or pipes beneath.

The form of tank here shown gives two advantages to the car: first, by its top terminating in an angle the oil is less likely to assume 55 a dangerous vibratory or wave motion from the sudden stoppage and starting of the car; secondly, the interior bottom of the upper box or car-body, following the slant of the tank, is well suited to the quick delivery at its central door, G, of grain carried in bulk, the same 60 sliding freely down the floor from the ends toward the center of the car.

E represents a pipe by which the oil-tank may be filled, and F a discharge-pipe therefor.

65 The tank may have any suitable provision for top vents to free it from gas in hot weather or from the effect of shaking. The tank might be built with a horizontal top, or a top of any other shape suited to receive a box-car on it; 70 but I prefer the top shown for the reason stated.

By means of my invention the tank may hold enough oil to be a full car-load to carry one way, and the box or car-body above it 75 may hold grain enough for a full load on the return-trip, and will deliver it readily at its door, thus effecting a great economy.

Having thus fully described my invention, what I claim, and desire to secure by Letters 80 Patent, is—

1. The combination of a tank, B, having a close top, sides, and ends, and mounted on wheels, and the body of a grain-car, consisting of a box, C, fitted on top of the tank, and 85 having a bottom, D, separated from the top of the tank by an air-space, and slanted on its bottom from its ends toward its middle, substantially as shown and described.

2. The combination of an oil-tank, B, practically separated into two compartments by its top slanting from the ends toward the middle, and a box or car-body fitted on the top thereof and having its bottom slanted from the ends toward the middle thereof, substantially as 95 shown and described, for the purpose specified.

In testimony whereof I affix my signature in presence of two witnesses.

JOHN R. GATHRIGHT.

Witnesses:

U. B. WILSON,
